(57) **CLAIM**

The ornamental design for a pet bed, as shown and described.

DESCRIPTION

FIG. 1 is a front, right, top perspective view of a pet bed, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is a front, right, top perspective view of the pet bed, indicating the first usage environment;

FIG. 11 is a rear, left, bottom perspective view of the pet bed, indicating the first usage environment;

FIG. 12 is a front, right, top perspective view of the pet bed, indicating the second usage environment; and,

FIG. 13 is a rear, left, bottom perspective view of the pet bed, indicating the second usage environment.

The dashed broken lines in the figures are for the purposes of illustrating portions of the pet bed and form no part of the claimed design.

The dash-dot-dash broken lines are for notating enlarged views and form no part of the claimed design.

The broken lines are for environmental purposes only and form no part of the claimed design.

1 Claim, 13 Drawing Sheets
